UNITED STATES PATENT OFFICE.

GOTTFRID HILDING KINBERG, OF HAMBURG, GERMANY.

COIN-COUNTER.

1,175,529.

Specification of Letters Patent. Patented Mar. 14, 1916.

Application filed August 27, 1912. Serial No. 717,272.

To all whom it may concern:

Be it known that I, GOTTFRID HILDING KINBERG, a subject of the King of Sweden, and resident of Hamburg, Germany, have 5 invented the new and useful Improvements in Coin-Counters, of which the following is a specification.

This invention relates to apparatus for counting coins or like objects, and has for 10 its object to provide an apparatus having means to insure the accuracy of its operation.

With this object in view my invention provides an apparatus having a movable plate 15 with apertures therein to carry the objects, and means for locking such plate against movement immediately an aperture therein is left vacant.

In the drawing similar letters refer to 20 similar parts.

Figure 1 shows the apparatus in a sectional elevation and Fig. 2 in plan. Fig. 3 is a detail showing the means for stopping the apparatus when the coins are exhausted, 25 Figs. 4 and 5 show a modification of these means.

In the construction shown in the drawings the chambers or partitions for moving the coins or other articles to be counted are 30 formed in a disk *b* rotating above a table *e* with a vertical shaft *a* suitably journaled. The disk is provided with a series of perforations or partitions *c* arranged in a circle and of a shape adapted to hold the coins *x* 35 or other articles to be counted. The coins *x* are stored up in the feeding funnel *d* arranged vertically in a position over one of the partitions *c* so as to allow the lowest coin to fall into the partition coinciding 40 with it, the distance of the lower end of the funnel from the table *e* corresponding to the thickest coin and the thickness of the disk corresponding with that of the thinnest coin or is somewhat thinner. Thus 45 only one coin can be caught hold of by each partition. The underface of the disk *b* is preferably made to touch the table *e* at least its distance from the same should be as small as possible. The table *e* is carried by four 50 legs or posts *f* and is provided below the path of the partitions *c* with an opening or perforation *g* opposite that side, on which the feeding funnel *d* is arranged. Below this opening there is the delivery chute *h*.

Above the disk suitable guides *n* are carried by a bracket *o* attached to the table, for

guiding a vertical locking bar *i*, which is adapted to enter into a partition of the disk next to the opening *c*, when there is no coin in such partition. Therefore, when the amount of coins is exhausted, the bar *i* will drop into the partition as soon as the last coin drops into the chute *h*. When the partitions are filled by a coin, this coin will prevent the bar from dropping down. A slot *k* 60 in the table, in line with the bar, allows the bar to penetrate the disk a sufficient distance to firmly hold it fast. This has the effect to arrest the disk, when the last coin has been delivered and thus to prevent a false registration. 70

In operation the disk *b* is quickly rotated for instance by conical gearings *b*¹ and *b*² and a crank *l* attached to the shaft of the gear *b*². In rotating the openings *c* in succession pass the funnel *d* and are each filled by a coin *x*, which is carried around half a circle on the table *e* and finally delivered into the chute, as soon as it is brought over the opening *g* of the table. Before the first 80 coin is carried to this point, the locking bar *i* is raised to clear the disk, whereupon it is allowed to drop down on the same ready to arrest its movement, when the last coin is paid out. The coins delivered by the chute *h* are caught by suitable bags or boxes. The rotation of the disk is transported by suitable known driving means to any known 85 counting and registering means not shown, from which the number of the counted coins 90 can be read off. Since it may happen that now and then bent coins are placed into the funnel, that part of the plate *e*, which is below the funnel *d* is made removable. In the construction shown it is made in the shape 95 of a slide *m*, which can be drawn out and pushed in again to remove the obstacle. The locking piece or bar is preferably rounded off at its lower edge, in order to allow it to mount the disk, when the upper 100 surface of the coins are not flush with the upper surface of the disk. This however causes the locking piece to vibrate up and down, when the disk is quickly rotated. This drawback will particularly take place, 105 when coins are counted that are of considerable less diameter than the chambers or openings in the disk. It may then even happen, that the locking piece penetrates the gap left between the rim of the coin and 110 that of the chamber, thus even stopping or hindering the movement of the disk. To

avoid this the locking piece is given a considerable broad foot so that it cannot fall down from the disk into a chamber until the coin is below the bearing face of the locking piece, as shown in Figs. 4 and 5. The locking-piece γ^1 shown in these figures has the shape of a piston of a diameter somewhat smaller than that of the smallest coins to be counted. Of course the opening k^1 for allowing the locking piece to descend, when there is no coin in the chamber should correspond to the cross section of the locking piece as before.

It will be clearly understood that the size of coins to be counted may vary, as long as they are larger than the diameter of the piston and smaller than that of the chamber. For still larger coins it will be necessary to exchange the disk for another, that is provided with correspondingly larger chambers.

I claim:

1. An apparatus for counting coins and the like comprising a coin feeding device, a fixed table having a delivery opening for said coins, a rotatable sheet having a series of equidistant perforations adapted to hold said coins singly and move them along the table, a standard mounted on said table at

a distance from said delivery opening substantially equal to that between the successive perforations in the sheet, and a locking piece adapted to slide within said standard and to coöperate with the perforations in the sheet to stop the rotation of same when the coins are exhausted.

2. An apparatus for counting coins and the like comprising a fixed table having a delivery opening for said coins and a smaller opening in proximity to said delivery opening, a movable sheet having a series of perforations forming chambers adapted to hold the coins singly and move them along on said table, a vertically slideable locking piece adapted to normally bear on the surfaces of the movable sheet or the coins respectively, the lower end of said locking piece being so shaped that it cannot drop into a perforation containing a coin although such coin be of the smallest size, and said small opening in the table being so shaped that said locking piece fits exactly into same when allowed to drop through an unfilled perforation.

GOTTFRID HILDING KINBERG.
